UNITED STATES PATENT OFFICE.

CLARENCE V. GREENAMYER, OF LOS ANGELES, CALIFORNIA, ASSIGNOR
TO WILLIAM HYMAN HOLABIRD, OF LOS ANGELES, CALIFORNIA.

TROLLEY-POLE CONTROLLER.

SPECIFICATION forming part of Letters Patent No. 782,195, dated February 7, 1905.

Application filed February 4, 1903. Serial No. 141,883.

To all whom it may concern:

Be it known that I, CLARENCE V. GREENAMYER, a citizen of the United States, residing at Los Angeles, in the county of Los Angeles and State of California, have invented new and useful Improvements in Trolley-Pole Controllers for Electric Cars, of which the following is a specification.

My invention relates to means for controlling by air-pressure the trolley-pole to give the wheel the necessary pressure on the trolley-wire and when the wheel accidentally leaves the wire to bring the free end of the pole down below the level of the span-wires until released, when the wheel may be replaced on the wire; and the object thereof is to provide efficient means to accomplish these results. I accomplish these objects by the mechanism described herein, and illustrated in the accompanying drawings, in which—

Figure 1 is a side view of a car equipped with my improved controller. Fig. 2 is a plan of so much of my controller as is placed upon the top of the car. Fig. 3 is a central longitudinal vertical section of the parts shown in Fig. 2, a portion of some of the front parts being shown in elevation. Figs. 4, 5, 6, and 7 are views showing details of the construction of some of the parts.

In the drawings, 1 represents the car. 2 is an air-brake reservoir attached to the bottom thereof, which furnishes air by means of which the brakes (not shown) are operated in the well-known manner, which reservoir supplies air to the trolley-pole controller. A pipe 3 connects this reservoir with swivel-pin 4, which unites spindle-base or roof-plate 5, secured to the roof of the car, with the base-swivel 6. This base-swivel is provided with arms 7 and 8, in which is pivotally mounted air-cylinder 9 by trunnions 10 and 11, secured to the sides of said cylinder and passing through holes in the ends of said arms. One of said trunnions 11 is hollow and is connected by pipe 12 with the swivel-pin, which pipe is rotatable therein. This pin has a channel 13 extending therethrough, which, with pipes 3 and 12, afford a passage for the

air from the reservoir to the interior of the front portion of the air-cylinder between piston 14 and the front of the cylinder. This piston, which will be called the "air-piston," is provided with a stem 15, preferably hollow, which is secured to a connecting-head 16. This head is pivotally united to the trolley-pole base-socket 17, in which is secured trolley-pole 18. This base-socket is preferably L-shaped and is pivotally secured to the base-swivel. Surrounding the stem of the air-piston within the air-cylinder is a spring 19, whose expansive force balances the weight of the trolley-pole and raises it to the wire. If desired, the weight of the trolley-pole may be balanced, and it may be held to the wire by an exterior spring 20, (shown in Fig. 1,) which engages an arm 21, affixed to the trolley-pole socket. Secured to the air-cylinder is the liquid-cylinder 22, to the top of which is secured liquid-reservoir 23, which is in communication with the cylinder through passage 24, which passage is controlled by check-valve 25, held normally open by spring 26, the tension of which is regulated by screw 27, passing in threaded contact through the top of the reservoir. The liquid-cylinder is provided with a piston 28, having stem 29, which is secured to head 16. The liquid-cylinder is provided with a short sliding piston 30, having a stem 31. (Shown enlarged in Fig. 4.) This piston has a limited movement just in the rear of passage 24. In the rear of this piston the bore of the chamber is slightly enlarged, and a tubular casing 32 is screwed therein. In the rear of the junction of this casing with the casing of the liquid-cylinder is an annular chamber 33, which is in communication through channel 34 with pipe 35, which pipe leads to and connects with trunnion 11.

Casing 32 is provided with a number of passages 36, which provide communication between chamber 33 and the interior of the casing. In this casing is a cup-shaped check-valve 37, having a number of notches 38 in the rear end thereof and a number of grooves 39 in sides thereof to permit the air entering

chamber 33 to have access to the interior and rear face of this valve. This valve normally keeps the opening through the tubular casing closed to prevent the air from passing there-through into passage 40, which passage is connected by pipe 41 with the rear portion of the air-cylinder back of piston 14. The rear closure of this air-cylinder is provided with relief-valve 42, which is an inwardly-opening 10 spring-pressed check-valve and is shown in detail in Fig. 5, in which *a* is the valve-stopper, provided with stem *b*, having a groove *c* in one side thereof for the passage of air to the chamber *d*, having port *e* in the casing 15 thereof. The valve-stopper is normally held off seat *f* by spring *g*, whose tension is regulated by screw *h*, a pin *i* limiting the movement of the stem.

A rope 43 is attached to the trolley-pole for 20 guiding the trolley-wheel to the wire in the usual manner.

A cut-off cock 44 is placed on pipe 3 at the end of the car to cut off the air from the controller, and a petcock 45 is provided above 25 cock 44 to bleed the air from the controller.

In the operation of my device after the trolley-wheel is placed on the wire, cock 44 is opened and air from the reservoir enters the air-cylinder in front of piston 14, thereby placing an air-pressure on the front face of the piston exerted in the same direction as the pressure of spring 19 to hold the trolley-wheel 30 in contact with the trolley-wire 47. It will be observed that by this construction the trolley-wheel is held in contact with the wire by 35 pneumatic pressure, which is quicker acting than spring-pressure and without the vibration of spring-pressure, and that therefore the wheel is less likely to leave the wire and also 40 prevents arcing by the solidity of its contact. The liquid-cylinder is filled with liquid between the pistons, and with the ordinary movement of the trolley-wheel on the wire as it adjusts itself to the varying height of the wire 45 the liquid flows into and out of the liquid-reservoir through passage 24; but on the sudden movement of the liquid caused by the wheel accidentally leaving the wire the check-valve in this passage is closed and the full force of 50 the movement of the liquid is exerted to move piston 30 to unseat valve 37. It will also be observed that the flow of air into and out of the air-cylinder in the rear of piston 14 is likewise provided for by relief-valve 42 when 55 the trolley-wheel is on the wire and that this valve is closed when the full air-pressure from the air-reservoir is admitted into the air-cylinder in the rear of piston 14. Now if the trolley-wheel accidentally leaves the wire the 60 combined spring and air pressure is exerted to send the trolley-wheel up into the air; but as the air-piston is connected to head 16 it must throw the upper arm of this head backward and downward. This arm carries liquid-

piston 28, and the full force of the air and 65 spring pressure is thereby imparted to the liquid in the liquid-cylinder, which causes it to move slide-valve 30 the full limit of its rearward movement and at the same time closes check-valve 25. This movement of piston 30 70 drives valve 37 off its seat and permits air from chamber 33 to fill the air-cylinder in the rear of piston 14 and close relief-valve 42. As the rear face of the piston has a much larger area than the other face of the piston subjected to air-pressure, the combined air and 75 spring pressure is quickly overborne and the trolley-wheel is caused to descend below the span-wires and all danger of their contacting with them is avoided. The downward movement of the front end of the air-cylinder through connecting mechanism causes the liquid-piston to move toward the front end of the cylinder, which brings slide-valve 30 back to its normal position. 80

To enable the replacement of the trolley-wheel upon the wire, cut-off cock 44 is closed and petcock 45 is opened, when the compressed air in the air-cylinder in the rear of piston 14 is permitted to escape. As soon as the pressure on the rear face of the piston is relieved the pole rises, and the trolley-wheel is guided to its position upon the wire by means of rope 43 in the usual manner. The petcock is then closed and the cut-off cock opened, and the 95 car is ready to proceed.

Having described my invention, what I claim as new, and desire to secure by Letters Patent, is—

1. In an electric railway having an overhead feed-wire, and supporting span-wires, a trolley-controller actuated by fluid-pressure whereby to maintain the required trolley contact on the wire, and to lower the trolley automatically to a predetermined point below 100 the span-wires when it accidentally leaves the trolley-wire.

2. The combination with a trolley-pole, of a controller comprising two cylinders, pistons pivotally connected with the pole and 105 adapted to slide in these cylinders, and a valve in position to be unseated by a sudden impulse of one of the pistons whereby to cause a fluid-pressure to be exerted on the other piston in a direction to reverse the movement 115 of the pistons and with them the pole.

3. In a trolley-pole controller the combination of a compressed-air reservoir with an air-cylinder having a piston operatively connected with the trolley-pole, said cylinder being in communication with said reservoir on both sides of the piston, the communication on one side of the piston being closed and the communication on the other side of said piston being open when the trolley-wheel is in 120 contact with the trolley-wire and having the piston area on said normally open side subject to air-pressure of less area than on the 125

other side; and means to open communication with said air-cylinder on the other side of the piston when the trolley-wheel leaves the trolley-wire.

5 4. In a trolley-pole controller the combination of a compressed-air reservoir; an air-cylinder pivotally connected to a support; a piston in said air-cylinder; a channel connecting said air-cylinder with said reservoir on the front side of said piston; a trolley-pole pivotally connected to the air-cylinder support; a stem connected to the front side of said piston and pivotally connected to said trolley-pole; a channel communicating with the channel leading from the reservoir and connecting with said air-cylinder in the rear of said piston; and means to keep said last-named channel closed when the trolley-wheel is contacting with the trolley-wire and to open the same 15 when the trolley-wheel leaves the wire.

5 5. In a trolley-pole controller the combination of a compressed-air reservoir; a support pivotally connected to the top of the car, an air-cylinder pivotally connected to the support; a piston in said air-cylinder; a channel connecting said air-cylinder with said reservoir on the front side of said piston; a trolley-pole pivotally connected to the air-cylinder support; a stem connected to the front side of 25 said piston having a head-block pivotally connected to the base of said trolley-pole; a channel communicating with said first channel and connecting with said air-cylinder in the rear of said piston; and means to control said channel, comprising a check-valve in said channel; and means to move said check-valve, comprising a chamber; a piston having a stem adapted to unseat said check-valve on the rearward movement of said piston, said piston being 30 slidably mounted in the rear portion of said chamber; a piston extending into the front end of said chamber and secured to the head-block of said first piston; liquid in said last chamber intermediate the pistons therein; and a liquid-reservoir communicating with said chamber in front of the piston in the rear end thereof.

5 6. In a trolley-pole controller the combination of a trolley-pole; a compressed-air reservoir; an air-cylinder having a piston operatively connected to the trolley-pole; a channel connecting said reservoir with said air-cylinder on both sides of the piston therein; a check-valve in the channel connecting the rear portion of said cylinder with said reservoir adapted to close said channel when the trolley-wheel is on the trolley-wire; and means to open said check-valve when the trolley-wheel accidentally leaves the wire, comprising

ing a liquid-operated piston having a stem 60 adapted to contact with and unseat said valve at said time.

7. In a pneumatic trolley-pole controller the combination of an air-operated piston operatively connected to the trolley-pole and a liquid-cylinder having two pistons therein with liquid therebetween, one of which is operatively connected with the piston of the air-cylinder, said pistons being adapted to open the valve closing the air-passage into the air-cylinder at the rear of the piston therein when the trolley-wheel accidentally leaves the wire.

8. In a pneumatic trolley-pole controller in which compressed air is used on both sides of the piston of the pneumatic cylinder, a check-valve in the passage leading to said cylinder in the rear of the piston therein adapted to keep said passage closed when the trolley-wheel is on the wire.

9. In a pneumatic trolley-pole controller in which compressed air is used on both sides of the piston of the pneumatic cylinder which controls the trolley-pole, and a check-valve is used to keep the passage to the rear of the piston closed when the trolley-wheel is on the wire, means to unseat said valve when the trolley accidentally leaves the wire comprising a hydraulic cylinder; a piston having a stem adapted to contact with and unseat said valve on the rearward movement thereof in the rear portion of said cylinder; a piston operatively connected with the trolley-pole in the front portion of said cylinder, liquid between said pistons, and a reservoir connected 95 with the space between said pistons substantially as described herein.

10. In a trolley-catcher, a trolley-pole, means for pressing the trolley-pole upwardly and downwardly, and mechanism for controlling said means.

11. In a trolley-catcher, a trolley-pole, pneumatic means for pressing the trolley-pole upwardly and downwardly and mechanism for controlling said means.

12. In a trolley-catcher, a trolley-pole, pneumatic means for pressing the trolley-pole upwardly and downwardly, a spring for assisting said means, and mechanism for controlling said means.

In witness that I claim the foregoing I have hereunto subscribed my name this 29th day of January, 1903.

CLARENCE V. GREENAMYER.
